Primary Examiner—Clare Heflin(74) *Attorney, Agent, or Firm*—Renner, Kenner, Greive, Bobak, Taylor & Weber(57) **CLAIM**

The ornamental design for a cable stripping tool, as shown and described.

DESCRIPTION

FIG. 1 is a right side elevation view of a cable stripping tool, the jaws of the tool being shown in a partially open position; FIG. 2 is a left side elevation view thereof;

FIG. 3 is a front elevation view thereof; FIG. 4 is an elevation view from the handle end thereof; and, FIG. 5 is a top view thereof with the jaws of the tool in the closed position, the bottom view being a mirror image thereof.

The broken lines shown on the drawings are for illustrative purposes only and form no part of the claimed design.
